[57] **CLAIM**

The ornamental design for a motorcycle carburetor and wire cover, substantially as shown.

DESCRIPTION

FIG. 1 is a left side elevational view of a motorcycle carburetor and wire cover embodying our new design in a position of use, it being understood that the broken lines are for illustration purposes only;

FIG. 2 is a left side elevational view thereof to an enlarged scale;

FIG. 3 is a right side elevational view thereof to an enlarged scale;

FIG. 4 is a rear elevational view thereof to an enlarged scale;

FIG. 5 is a front elevational view thereof to an enlarged scale;

FIG. 6 is a top plan view thereof to an enlarged scale; and

FIG. 7 is a bottom plan view thereof to an enlarged scale.
